[57] CLAIM

The ornamental design for an attachment for a blowing machine, as shown.

DESCRIPTION

FIG. 1 is a perspective view of an attachment for a blowing machine showing my new design;

FIG. 2 is a front elevational view of the attachment shown in FIG. 1; the rear elevational view thereof being a mirror image;

FIG. 3 is a top plan view of FIG. 1;

FIG. 4 is a bottom plan view of FIG. 1;

FIG. 5 is a right side elevational view of FIG. 1; and

FIG. 6 is a left side elevational view of FIG. 1; and,
FIG. 7 is a sectional view taken along lines 7—7 in FIG. 1.
